UNITED STATES PATENT OFFICE.

BURDETT LOOMIS, OF HARTFORD, CONNECTICUT, AND HAWLEY PETTIBONE, OF NEW ROCHELLE, NEW YORK.

METHOD OF MAKING AND DELIVERING GASES.

No. 863,780.

Specification of Letters Patent.

Patented Aug. 20, 1907.

Original application filed December 7, 1903, Serial No. 184,144. Renewed March 14, 1906, Serial No. 306,014. Divided and this application filed September 15, 1906. Serial No. 334,792.

To all whom it may concern:

Be it known that we, BURDETT LOOMIS and HAWLEY PETTIBONE, citizens of the United States, residing, respectively, at Hartford, in the county of Hartford and 5 State of Connecticut, and at New Rochelle, in the county of Westchester and State of New York, have invented certain new and useful Improvements in Methods of Making and Delivering Mixed Gases to Gas-Engines, of which the following is a specification.

10 This invention relates to an improved method of making, delivering, storing and mixing gases of any desired calorific value, and in any desired proportions of their constituents relative to their heat units so as to have them adapted for motive power in high-power 15 gas-engines, and to improvements in the method of operating such engines in connection with an apparatus such as aforesaid.

The object of the invention is to provide for generating a gas of the nature of that generally termed producer-gas and also a gas of the nature of that termed water-gas, drawing them from the generating or producing furnaces by exhaust action or equivalent means and, during the manufacture, and while they are subjected to the action of exhaust, mixing the gases of the 25 two kinds in a predetermined proportion to have them give the most effective and economical results as a motive agent in an explosive engine of several hundred horse-power.

Heretofore gas engines have been operated by illuminating gas, and attempts have been made to operate engines of one hundred horse-power and more with water-gas. But the flame temperature and heat units of such gas have been found to be too high to give satisfactory results. The explosions produced by water- 35 gas, owing probably to the large percentage of hydrogen therein, are too sharp and quick; the inertia of the heavy engine parts is too great to be efficiently overcome; the gas is apt to fire back; and the engines are so strained and racked that an uneven power is generated.

Water gas ignites at so low a temperature that when properly mixed with air for the explosive charge in a gas engine the charge will explode prematurely during compression, due to the heat caused by compression 45 and the hot internal parts. The effect of a premature explosion is to immediately slow down the engine and put undue strain on its working parts. Since the efficiency of a gas engine increases with the compression of the charge it is important to have a gas that will 50 stand high compression.

On the other hand, a gas having the characteristics of producer-gas, has also been found to be not available

because of the large percentage of carbonaceous constituents—unfixed carbon and nitrogen, these not only causing sluggishness in the explosion, but also tending to leave so large a quantity of residual matter in the form of sooty or tarry bodies as to seriously interfere with, and finally render inoperative the various ports or passageways and the valves and small moving parts of the engine.

By varying the calorific value and constituents of the gas produced and delivered by the one apparatus, a mixture can be made of such quality as is best adapted for use in the particular engine it must operate.

We have found that a mixture of water-gas and producer-gas in predetermined proportions (varied to meet the variations in the constitution of the gases due to variations in the constituents of the initial fuel material and to variations in conditions of production) gives a substantially uniform body which can be used with great efficiency in high power explosive engines.

The various steps which we follow and the various devices which we employ from the time the fuel is initially introduced to the time that it is exploded in the engine will be readily understood from the description below, taken in connection with the drawings herewith presented which illustrate mechanism that can be used for this purpose, and illustrate also a series of steps such as conform to our improved process.

Figure 1 shows in side elevation one form of apparatus by which our improved method can be carried out, of operating a gas engine and supplying it with a proportioned mixture of producer-gas and water-gas. Fig. 2 is a rear elevation of the connected generators and a steam boiler, parts being shown in sections. Fig. 3 is a top plan view of Fig. 1, showing an apparatus containing our improvements.

The generators A and B are constructed of brick enclosed in iron jackets in the usual manner and are provided with grates b, of any desired construction, and with ash pits X. The generators are connected at the top by a pipe or flue C, and are connected at the base or ash pits X by gas outlet pipes D, D', having valves d, d'—with the base of the tubular steam boiler E, having at top and bottom, the gas chambers e, e' and tubes e'' connecting the upper and lower tube sheets. A gas outlet pipe F, having a valve f, connects with the upper gas chamber e and with the base of the scrubber G, and a gas outlet pipe H, having a valve h, leads from the top of the scrubber down to the main gas exhauster K. The main gas take-off pipe L leads from the under side of the exhauster and connects by the branch pipe L', having a valve l', with the holder O for producer-gas or a mixture of producer-gas and water-gas. A branch

- pipe having a valve l connects pipe L with the purge stack M for the escape of waste gases, or products of combustion. A branch pipe N , having a valve n , leads from the pipe L into holder P for water-gas.
- 5 The pipe T , having a valve t , leads from the holder P and connects with the top of the small exhauster R . The discharge pipe T' from exhauster R is provided with a valve t' and connects with pipe L' beyond its valve l' for supplying a definite proportion of water-
- 10 gas and mixing it with the producer-gas which is being passed through pipe L' into the holder O . A by-pass and circulating pipe r , having a valve r' , connects the outlet pipe T' with the inlet pipe T of the exhauster R . A by-pass and circulating pipe k connects the 15 outlet pipe L with the inlet-pipe H of the exhauster K , and is provided with the valve k' . The exhauster K is driven by the engine I having a shaft i which is coupled directly to the shaft of the exhauster. The opposite end of the shaft i is provided with a cone pulley g , which connects by a belt o with a cone pulley g' on the shaft of the auxiliary exhauster R . When both 20 holders are full, or holder O , only, is full of gas, or if for other reason it is desired to stop, or reduce the generation of gas, the valve k' in by-pass pipe k may be opened, 25 while the exhauster is kept running, and gas will be circulated through the exhauster, its inlet and outlet pipes and by-pass pipe k . This is more satisfactory than stopping the exhauster and then starting it again when it is desired to resume the production and withdrawal of gas. In a similar manner the by-pass pipe r and valve r' may be used for circulating water-gas instead of stopping the exhauster R . Steam supply pipes S and S' connect by branch pipes s and s' , each 30 having a valve, with the top and bottom of each of the generators A and B for supplying steam to be passed either up or down through the bodies of incandescent fuel in making water-gas. A gas outlet-pipe Q , having a valve q , leads from holder O for taking mixed producer-gas and water-gas to a gas-engine W , and a 35 branch pipe may take gas to any other place of use.
- W indicates a gas engine connecting by pipe w with holder U . This engine W may be of any of the usual styles or of any preferred sort so far as concerns the principle of construction of its several parts. The 40 present invention is more particularly applicable to gas engines of the larger and more powerful sorts. In these are used large pistons having long strokes and of correspondingly large parts connected therewith, or directly related thereto. At each stroke the piston 45 exerts a powerful suction action, by means of which gas is drawn through pipe Q which communicates with holder O .
- With the apparatus shown in Fig. 3, the operation of making and mixing producer-gas and water-gas and 50 supplying the engine may be conducted as follows: Fires are kindled on the grates in generators A and B , and at first allowed to burn by natural draft while fuel is gradually fed in and ignited. The valves l' and n being closed, and the stack valve l and other valves between the stack and generators being open and the lids z wholly, or partly, open, the exhauster K is operated to draw air down into the bodies of ignited fuel, and draw the resulting gas off from the bases of the generators, through boiler E and scrubber G , and discharge 55 it up the stack M . As soon as good producer-gas is

generated the stack valve l is closed, valve l' opened, and the producer-gas is discharged into the holder O . The stack valve l is only open while the bodies of fuel are being heated to the proper condition for making gas.

Deep bodies of fuel in generators A and B , having 70 been heated to incandescence, water-gas may be made, and for this purpose the top lids x are closed, valve d' closed, valve l' closed, valve n opened and steam valve s' opened, admitting steam into the ash pit of generator A . Steam passes up into the body of 75 incandescent fuel in generator A where it is decomposed and the resulting water-gas passes through top pipe C into generator B and thence down through the body of incandescent fuel therein, where any accompanying vapors are decomposed, and carbonic acid 80 converted into carbon monoxide, making a well-fixed high grade water gas. This gas is drawn off by the exhauster through pipe D , boiler E , and scrubber G and discharged into the water-gas holder P . Water-gas is thus made till the temperature of the fuel is reduced 85 too low for effectively decomposing steam and then the steam is shut off, the top lids x opened, valve d' opened, valve n closed and valve l' opened and producer-gas again made and delivered into the holder O .

When it is again desired to make water-gas we preferably close valve d in gas outlet pipe D , and admit steam into the base of generator B . Steam is then decomposed by passage up through the incandescent fuel in generator B , and the resulting gas down through the bed of fuel in generator A , and the resulting water-gas is drawn off by the exhauster through pipe D' , the steam boiler and scrubber, and discharged into holder P . 90

A sufficient quantity of water-gas having been stored in the holder P , the auxiliary exhauster R is used to deliver a fixed proportion of water-gas with producer-gas into the holder O for mixed gas. The exhauster R and the valves r' and t' are operated as follows:

When the exhauster K is operating and delivering producer-gas through valve l' , the valves t and t' are opened and the by-pass valve r' is closed, and the 105 exhauster R will operate to draw water-gas from the holder P and deliver it through pipe T' into the holder O at a rate proportional to the delivery of producer-gas by the exhauster K .

By shifting the belt o on the cone pulleys g and g' , 110 the proportion of water-gas to producer-gas can be increased or decreased. The mixture of water-gas and producer-gas in definite and any desired proportions can thus be stored in the holder O and delivered to gas engines or other places of use.

When water-gas is being delivered through valve n to the holder P , valve t' may be closed and the by-pass valve r' may be opened, so that no water-gas passes into the mixed gas holder O , except when producer-gas is also being delivered into said holder O . 120

After a measured volume of producer-gas has been stored in holder O , the supply of producer-gas thereto may be stopped, and then a measured volume of water-gas is passed into holder O , being drawn from holder P , or directly from the generator. The gases will mix 125 by diffusion in holder O and may be delivered, in a suitably mixed condition, therefrom to gas-engine W .

It will be understood that the dimensions of the parts which generate the gas, as well as those by which the gas is carried from point to point and those of the stor- 130

ing vessels or holders, and also the speeds of the several operative parts, will be particularly related to the capacity and demand of the gas engine W so that there will be as near as practicable a constant quantity 5 of accurately proportioned and commingled gases in the holder U, ready to sustain the operation of the engine..

Gas-engines of the heavy power class require, first, explosions of a peculiar character, second, cleanliness 10 after explosion, and, third, that the explosion should be relatively prolonged in time. If a gas similar to producer-gas and having only the qualities and characteristics of that gas be delivered, alone, to the gas engine it may furnish material for explosions, but these 15 are accompanied by, or result in, several disadvantageous matters, as for instance, a slowness and sluggishness in the firing of the gas or explosion with liability of incompleteness of combustion, secondly, the depositing of carbonaceous matters of a sooty or tarry 20 character. On the other hand, if a gas having the qualities and characteristics of water-gas be delivered alone, to a gas engine explosions will occur which, though they may not result in the disadvantages incident to the producer-gas, and will leave the valves and 25 other parts of the engine in a cleanly condition, are nevertheless, not efficient with engines of the larger sort, as the impulses are too quick, short, sharp and violent, and will not work advantageously in a long or laterally expanded explosion chamber or piston-driv- 30 ing chamber.

Instead of operating a gas-engine with gaseous bodies of the above sorts we provide an explosive agent containing intelligently and accurately predetermined proportions of these two widely differing gaseous bodies 35 with the result that the producer-gas is, by the water-gas, caused to more thoroughly and uniformly and somewhat more rapidly explode than would be the case if it were used alone, and the producer-gas by more complete combustion and explosion leaves the 40 engine parts in a cleanly condition; while, on the other hand, the water-gas is, by the intermingling producer-gas, checked with respect to the quickness, sharpness and violence of its explosions. By first completely separating the two kinds of gas and then accurately 45 commingling them in proportions subject to variation corresponding to the variations in their constitution which result from different fuel materials or from different conditions in production, the gas engineer is provided with a means for obtaining explosions with com- 50 plete combustion and of such character that he can impart to his large and relatively slowly moving piston exceedingly efficient energy impulses.

We do not herein present specific claims for the combination of generator, exhauster, a holder for the producer gas, a holder for water gas, and means for supplying gas from one holder to the other, preparatory to supplying the mixture to the gas engine, as we have presented that specific subject matter in claims in our application Serial No. 306,014, originally filed December 7, 1903, and co-pending with this present case, and on which application Patent No. 833,137 was issued, October 9, 1906, of which application, Serial No. 306,014, the present is a division.

Having described our invention, what we claim, and desire to secure by Letters Patent, is—

1. The method of operating a gas engine and supplying explosive mixed-gas thereto, consisting in first passing air through a chamber containing a body of ignited fuel and drawing from said chamber a volume of producer gas, cleaning said gas, and storing it in a holder, forming a 70 volume of water-gas by passing steam through said body of fuel and storing it separately from said producer gas, then commingling in a gas holder or otherwise predetermined quantities of each of said gases and withdrawing volumes of the mixture and delivering them directly to a 75 gas engine and exploding them therein, substantially as described.

2. The method of operating explosive gas engines and of supplying explosive gases thereto, which consists in depositing carbonaceous material in a gas-producing chamber, forming therewith during intervals gas substantially such as is termed producer-gas, withdrawing the said gas and temporarily storing it as a separate body in a holder and at intervening intervals generating in said fuel water-gas, withdrawing said water-gas and storing it in a separate temporary holder, subsequently commingling volumes of the producer-gas and volumes of the water-gas in variable but predetermined proportions at will, drawing charges of the said commingled gases into, and exploding them in, the explosion chamber of a gas engine, said steps being prosecuted substantially as set forth, whereby the sharpness and quickness of the explosions of pure water-gas are avoided and said water-gas is utilized to cause the complete and uniform explosive reaction of the constituents of the producer-gas, substantially as described.

3. The herein described method of operating gas engines and supplying gas thereto, consisting in first producing a volume of gas of the character of producer gas, cleaning, cooling and storing it in a holder, forming separately a volume of water-gas, cleaning, cooling and storing it in a separate holder, causing variable quantities of the said separately collected gases to be commingled in predetermined proportions, and delivering the mixture to, and causing its explosion in the engine, substantially as set forth.

In testimony whereof we affix our signature in presence of two witnesses.

BURDETT LOOMIS.
HAWLEY PETTIBONE.
